UNITED STATES PATENT OFFICE.

JOHN F. TOOMEY, OF NEW YORK, N. Y., ASSIGNOR TO AMERICAN TELEPHONE AND TELEGRAPH COMPANY, A CORPORATION OF NEW YORK.

THROUGH-RINGING REPEATER-CIRCUITS.

1,364,159.

Specification of Letters Patent.

Patented Jan. 4, 1921.

Application filed January 31, 1917. Serial No. 145,672.

To all whom it may concern:

Be it known that I, JOHN F. TOOMEY, residing at New York city, in the county of New York and State of New York, have invented certain Improvements in Through-Ringing Repeater-Circuits, of which the following is a specification.

This invention relates to telephone repeater circuits and more particularly it relates to two-way two-repeater circuits with which is associated means for relaying ringing current or other signaling current as distinguished from telephone current. Its object is to provide means for automatically associating the ringing relay with the system upon the receipt of ringing current, for protecting the telephone repeaters from the incoming and relayed ringing current and for disconnecting the ringing relay and its associated apparatus upon the cessation of the incoming ringing current.

My invention is best understood by reference to the accompanying drawings in which Figures 1 and 2 when placed side by side constitute a diagram of a two-way two-repeater telephone station.

Referring to the drawing a two-way two-repeater station is shown which embodies the arrangements of my invention for relaying ringing current past said repeater station. The repeater arrangement comprises two vacuum tube repeaters R and R', and their associated apparatus, repeater R being adapted to receive signals transmitted to the station over line 1 and to transmit amplified copies of said signals from the station over line 1'. Circuit 2 is the input circuit of repeater R and is normally bridged across line 1 through contacts 4, 4 of relay 5, while its output circuit 3 is inductively associated with line 1'. Input circuit 2' of repeater R' is normally bridged across line 1' while its output circuit 3' is inductively associated with line 1, and said repeater is therefore adapted to receive signals transmitted to the station over line 1' and to retransmit, after amplification, said signals out over line 1. Since said repeater station consists of two symmetrical halves or sections, corresponding elements in said halves will be denoted by the same numerals, with and without primes respectively. Since the operation of said telephone repeaters is no part of my invention and is well known, the

description of the invention will be limited to the arrangements concerned with the transmission of ringing currents from line 1 to line 1' and vice-versa.

Assume that a ringing current or other current having characteristics differing from those of telephonic or signaling currents which actuate the repeater is transmitted to the station over line 1. This ringing current passes from line 1 through contacts 4, 4 of relay 5 and due to its different characteristic, energizes relay 6, thereby opening contact 7, deenergizing relay 8 and closing contact 9. Relay 6 is in parallel with input circuit 2 of repeater R but is not operated by the relatively feeble high frequency telephonic currents. The closing of contact 9 establishes a circuit from ground through battery 10, the winding of relay 11, thence through conductors 12 and 13' through the winding of relay 5' and thence through contact 9, conductor 14 and the winding of relay 15 back to ground, with the result that relays 11, 5' and 15 are simultaneously energized. The actuation of relay 11 opens contacts 16 and 16' and closes contacts 17 and 17'. The closing of contact 17 short-circuits the primary of repeating coil 18 while the opening of contact 16 open-circuits input circuit 2 thus cutting repeater R out of service and removing a shunt which normally exists across relay 6. The operations of contacts 16' and 17' in precisely similar manner cut repeater R' out of service and remove a shunt which normally exists across relay 6'. The repeaters are therefore protected from the ringing current by the operation of relay 11 and it will be clear that repeater R is affected by the ringing current only during the brief interval between the arrival of the ringing current and the actuation of relay 11.

The actuation of relay 5' opens contacts 4', 4' and closes contacts 19', 19' thereby disconnecting line 1' from the repeater system and connecting it to circuit 20 which provides an auxiliary path for the transmission of ringing current. The actuation of relay 15 closes the following circuits: from ground through contact 22 and the interrupter 26 to 16 cycle ringing current generator thereby causing the interrupter to operate and generate 133 cycle ringing current. A second circuit is also established from ground through contact 24 of relay 15 and

the winding of relay 23 to battery thereby causing relay 23 to operate and connect the 133 cycle ringing current generated by interrupter 26, over circuit 28 through contacts 5 29, 29, to circuit 20 and thence through contacts 19', 19' of relay 5' to line 1'. It will be seen that since relay 5 is not energized circuit 20 is connected to line 1' only and not to line 1 so that the relayed ringing current is transmitted out over line 1' only.

To summarize the operations traced in detail above, the arrival of ringing current over line 1 initiates a cycle of operations commencing with the actuation of relay 6 15 which results in cutting the input circuits of repeaters R and R' out of service, thereby protecting said repeaters from the ringing current, disconnecting line 1' from the repeater system and connecting it to the output 20 circuit of the ringing interrupter and in setting the interrupter in operation.

The position of all the relays is controlled either by relay 6 or 6' so that the above described circuit connections remain established 25 so long as relay 6 is energized by the incoming ringing current over line 1. When said incoming ringing current ceases the circuit connections for repeater operation are reestablished as follows:

With the cessation of ringing current on line 1 relay 6 is deenergized, contact 7 is thereby closed and the energizing circuit of relay 8 is closed through said contact and said relay is energized. As a consequence 35 of the actuation of relay 8, which together with relay 8' is normally energized for repeater operation, contact 9 is opened thus putting the contacts of relay 8 in the same position as those of relay 8'. The opening 40 of contact 9 opens the circuit through the windings of relays 11, 5' and 15, thus deenergizing said relays and restoring the circuits to normal.

The deenergizing of the relay 5' results in 45 the opening of contacts 19', 19' and the closing of contacts 4', 4' thereby disconnecting line 1' from circuit 20 and connecting it with the repeater system. The deenergizing of relay 15 opens contacts 22 and 24 thereby deenergizing relay 23 and opening circuit 50 25 of interrupter 26. Relay 23 in releasing opens the connections between circuits 20 and 28 thereby disconnecting the interrupter from circuit 20. It will then be seen that 55 with the exception of relays 6 and 6' the apparatus associated with the ringing circuits and operations is completely cleared from any connections with the system, leaving the normal connections and circuit arrangements 60 for repeater operation. The windings of relays 6 and 6' remain bridged in parallel with repeater input circuits 2 and 2' respectively but any serious losses due to the presence of said relays may be minimized 65 by inserting retardation coils 31, 31 in

series with the winding of relay 6 and similar retardation coils 31', 31' in series with the winding of relay 6'. These retardation coils may be designed to have a very high impedance at telephonic frequencies so that 70 the shunting effect of said relays on the repeater input circuits is rendered negligible

When the ringing current is transmitted to the repeater station over line 1' the operation is precisely analogous to that described above. Relay 6' is energized instead of relay 6, thereby establishing a circuit for relays 11, 5 and 15 similar to that already traced for relays 11, 5' and 15. The actuation of relays 11 and 15 results in 80 the same operations as have been already described. The actuation of relay 5 disconnects line 1 from the repeater system and connects it to circuit 20. Line 1 is consequently connected through circuit 20 to the 85 outgoing circuit 28 of ringing relay 26 so that the relayed ringing current is transmitted out over line 1. Since relay 5' remains unactuated circuit 20 is not connected to line 1' and no relayed ringing current is 90 transmitted back over line 1'. The operations consequent upon the cessation of ringing current in line 1' and the deenergization of relay 6' need not be described since they will be clearly understood from the previous 95 description of the restoration of the repeater circuit connections consequent upon the deenergization of relay 6.

While the invention has been shown as embodied in a certain specific organization, 100 it will be understood that it is capable of embodiment in many and varied forms without departing from the spirit of the appended claims.

What is claimed is:

1. In a signaling system two line sections for transmitting signals of different characteristics, a device responsive to signals of one characteristic for relaying currents of that characteristic derived from a local 110 source from one line section to the other and means responsive to signals of another characteristic for relaying signals of the latter characteristic derived from a local source from one line section to the other.

2. In a signaling system, two transmission line sections, a repeater system for interconnecting the line sections, an auxiliary path for interconnecting said line sections, and means whereby in response to ringing current from one line section ringing current from a local source is relayed to the other section over said auxiliary path.

3. A telephone transmission system comprising two line sections, a repeater for interconnecting the line sections and means responsive to ringing current transmitted over either line section to disconnect the repeater and apply a local source of ringing current to the other line section.

4. A telephone repeater system comprising two line sections, repeaters for interconnecting said line sections, an auxiliary circuit for connecting said line sections, said circuit being normally disconnected from both of said line sections, a source of ringing current and means responsive to ringing current received over either line section to disconnect the other line section from 55
 5 said repeaters, to connect it to said auxiliary circuit and to apply said source of ringing current to said auxiliary circuit.
5. A telephone repeater system comprising two line sections, repeaters normally 60 connecting said line sections, a source of ringing current and means responsive to ringing current received over either line section to connect said source of ringing current to the other line section and to cut 65
 10 said repeaters out of circuit.
6. A telephone repeater system comprising two line sections, repeaters connecting said line sections, a normally idle source of ringing current and means responsive to 70 ringing current received over either line section to set said source of ringing current into operation, to connect said source of ringing current to the other line section and to open the circuits of said repeaters. 75

7. In a telephone repeater system, the combination of two line sections, two one-way repeaters associated with said line sections and a ringing current relay, with means operable upon the receipt of ringing current over either line section for cutting the input circuits of said repeaters out of service, means controlled by said first mentioned means for disconnecting the other line section from the repeater system and connecting it with an outgoing circuit controlled by said ringing relay, and means for setting said ringing relay into operation.
8. A telephone repeater system comprising two transmission line sections, two one-way repeaters having input and output circuits, a source of ringing current, a relay associated with each line section each relay being responsive to ringing current received over its associated line section and relays controlled by said first mentioned relays for cutting the input circuits of said repeaters out of service, for setting said source of ringing current into operation, and for disconnecting the other line section from
- the repeaters and connecting it to said source of ringing current.
9. A telephone transmission system comprising two line sections, a repeater for interconnecting the line sections and means responsive to signaling current transmitted over one line section to disconnect the repeater and apply a local source of signaling current to the other line section.
10. A telephone system comprising two line sections, means to interconnect said line sections for transmission of amplified signaling currents of one character, and means responsive to currents of another characteristic from either line section for relaying similar currents from a local source to the other line section.
11. A telephone repeater system comprising two line sections, repeaters connecting said line sections, a normally idle source of signaling current and means responsive to signaling current received over either line section to set said source of signaling current into operation, to connect said source of signaling current to the other line section and to render the repeaters inoperative.
12. A signaling system, two transmission line sections, an amplifying means for interconnecting the line sections and an auxiliary path for interconnecting said line sections and means responsive to signaling currents from one line section for transmitting similar currents from a local source to the other line section over said auxiliary path.
13. In a signaling system, two transmission line sections, means to connect said transmission line sections for amplifying telephone currents transmitted over said line sections and means responsive to weak signaling currents of a different character received over one line section for applying strengthened currents of the same character to the other line section.
- In testimony whereof, I have signed my name to this specification in the presence of two subscribing witnesses, this 19th day of January 1917.
